United States Patent Office

Des. 210,790
Patented Apr. 16, 1968

210,790

GAME DEVICE

Alfred E. Ischinger, 410 Kenhorst Blvd.,
Reading, Pa. 19602

Filed Feb. 6, 1967, Ser. No. 5,698

Term of patent 14 years

(Cl. D34—5)

Fig. 1.

Fig. 2.

FIGURE 1 is a top plan view of a game device showing my new design, as seen by looking in the direction of the arrow in FIG. 2;

FIG. 2 is an edge view of the device as seen by looking toward FIG. 1 from the right, and

FIG. 3 is a bottom view of the device.

The dominant features of my design reside in the portions shown in full lines.

I claim:

The ornamental design for a game device, substantially as shown and described.
